UNITED STATES PATENT OFFICE.

JAMES W. SUPORTER, OF CHICAGO, ILLINOIS, ASSIGNOR TO C. A. NORTON, OF CHICAGO, ILLINOIS.

DESIGN FOR A RADIATOR CAP.

Application filed September 22, 1924. Serial No. 10,859. Term of patent 14 years.

To all whom it may concern:

Be it known that I, JAMES W. SUPORTER, a citizen of the United States, residing at Chicago, in the county of Cook and State of Illinois, have invented a new, original, and ornamental Design for a Radiator Cap, of which the following is a specification, reference being had to the accompanying drawing, forming a part thereof.

On the drawing,

Figure 1 is a front elevation of a radiator cap in which my invention is embodied; and Fig. 2 is a side elevation thereof.

I claim:

The ornamental design for a radiator cap as shown.

JAMES W. SUPORTER.

Witnesses:

CARL S. LLOYD,
GRACE L. LYNN.
